UNITED STATES PATENT OFFICE.

GEORGE LJESO, OF GRAFTON, WEST VIRGINIA.

PORTABLE FENCE AND CONVEYER FOR THE SAME.

1,161,704.

Specification of Letters Patent. Patented Nov. 23, 1915.

Application filed April 9, 1915. Serial No. 20,196.

To all whom it may concern:

Be it known that I, GEORGE LJESO, subject of the King of Hungary, residing at Grafton, in the county of Taylor and State of West Virginia, have invented certain new and useful Improvements in Portable Fences and Conveyers for the Same, of which the following is a specification.

This invention relates to certain new and useful improvements in portable fences and conveyers for the same.

The primary object of the invention is to provide a fence in complete sections ready for assembling and positioned when not in use upon a wagon for ready transportation to the desired location.

A further object of the invention is to provide fence sections with ground-engaging braces foldably mounted thereon, the sections having upper and lower wheel members for slidably positioning the same upon a transporting vehicle.

A still further object is to provide a wagon with upper and lower longitudinal tracks adapted for the reception of complete fence sections whereby the sections may be transported to the places desired and readily assembled in a fence formation.

With these general objects in view and others that will appear as the nature of the invention is better understood, the same consists in the novel combination and arrangement of parts hereinafter more fully described, illustrated in the accompanying drawings, and pointed out in the appended claims.

In the drawings forming a part of this application and in which like-designating characters refer to corresponding parts throughout the several views, Figure 1 is a side elevation of the device. Fig. 2 is a top plan view thereof. Fig. 3 is an end elevational view of the same. Fig. 4 is a detail vertical sectional view transversely of the section adjacent one of the struts thereof. Fig. 5 is a vertical transverse sectional view through a fence section, and Fig. 6 is a perspective view of one of the fence sections set up for use.

Referring more in detail to the drawings, the device broadly consists in providing a plurality of fence sections 10 which are adapted for easy assembling and are removably slidably mounted upon a vehicle 11 for the purpose of transportation. The wagon 11 has mounting wheels 12 and is provided

with a bottom 13 having parallel longitudinally arranged tracks 14 thereon and extending for its entire length. Opposite end frames 15 are provided having track bars 16 arranged parallel and secured between the top cross pieces 17 of the said frames, the said bars 16 being arranged parallel with and directly above the bottom tracks 14.

The fence sections 10 are arranged with end posts 18 having top and bottom extensions 19 for journaling rollers 20 therein, while the rails 21 of the fence are arranged parallel extending between the end posts and may be provided with any desired form of pickets 22.

Positioning struts 23 are arranged, two in number being herein shown, and are adjustably mounted upon the fence sections by means of rods 24 secured centrally to the struts and being slidably journaled through the lower two rails 21. By this arrangement it will be seen that the rods 24 may be inwardly positioned with the struts 23 lying slightly spaced below the lower rail 21 and whereupon the rail lugs 25 are brought between the spaced lugs 26 arranged adjacent the opposite ends of the struts so that the locking pins 27 may engage said lugs, locking the struts in their elevated inoperative positions, and in the same vertical plane as the lower fence rail 21. A head 28 is provided at the upper end of each of the rods 24 to which head opposite chains 29 are attached, the said chains being adapted for engagement by the pins 24 and between the strut lugs 26 when the section is arranged in its fence formation upon the ground as shown in Fig. 2. Engaging spikes 30 may also be employed extending through the ends of the struts and driven into the ground. By this arrangement of bars 16 above the bottom rails 15, it will be seen that separate fence sections may be readily positioned between these tracks and mounted thereon by means of the upper and lower rollers 20, the sections being slid inwardly upon the wagon to the positions shown in Figs. 1, 2 and 3 of the drawings. When the sections are so arranged upon the wagon, 105 they may be readily retained by arranging cross slats 31 upon the cut-away portions 32 of the fence section rails, such slats being secured by means of vertically positioned pins 33 extending through the said rails and slats, 110 the slats being so arranged forwardly of the front posts 15 of the wagon as best illus-

trated in Fig. 2. When the fence is desired for use, the wagon is propelled to the desired point and the separate fence sections 10 are slidably removed therefrom, and are 5 pushed along upon the lower rollers 20 until the desired location is reached, whereupon the pins 27 are released and the struts revolved to positions perpendicular to the sections and are lowered upon the ground being 10 retained in the manner hereinbefore described.

A wagon of any desired size may be employed for holding and transporting as many fence sections as may be required and the 15 length thereof being arranged accordingly, while the sections will be thus kept in a convenient position for storing when not in use, and can be moved and assembled in fence formation whenever desired.

20 The rollers 20 may be removed from the post ends 19 by removing the axle pins 34 when the sections are set up for use as shown in Fig. 6 or the said wheels 20 may be allowed to remain upon the sections at all 25 times if desired.

While the form of the invention herein shown and described is what is believed to be the preferred embodiment thereof, it is nevertheless to be understood that minor 30 changes may be made without departing

from the spirit and scope of the invention as set forth in the claims.

What I claim as new is:—

1. A device of the class described comprising in combination with a wagon having upper and lower spaced tracks arranged thereon, fence sections having end posts, and wheels journaled in the upper and lower ends of the said posts and adapted for mounting upon the said wagon between the 40 said upper and lower tracks thereof.

2. A device of the class described comprising in combination with a wagon having upper and lower spaced tracks arranged thereon, fence sections having end posts, 45 wheels journaled in the upper and lower ends of the said posts and adapted for mounting upon the said wagon between the said upper and lower tracks thereof, rods vertically slidably mounted upon the said 50 sections, struts secured to the lower ends of the said rods, and locking means between the said struts and fence sections when the struts are folded against the bottom thereof.

In testimony whereof I affix my signature 55 in presence of two witnesses.

GEORGE LJESO.
